UNITED STATES PATENT OFFICE.

CHARLES E. GRANT, OF CHICAGO, ILLINOIS.

HOISTING-MACHINE.

No. 893,919.

Specification of Letters Patent.

Patented July 21, 1908.

Application filed August 1, 1907. Serial No. 386,616.

To all whom it may concern:

Be it known that I, CHARLES E. GRANT, a citizen of the United States, residing at Chicago, in the county of Cook and State of Illinois, have invented a new and useful Improvement in Hoisting-Machines, of which the following is a specification.

My invention relates to that class of machines used in or about buildings under construction for raising the building material, and which are operated by horse power.

The object of my invention is to provide a shift mechanism forming part of the machine which is operable at the point where the load is removed from the car and at the point where the horse power is applied to the machine, a shift mechanism that can be operated by hand to reverse and stop and lock the power mechanism at any point in its movement, that will provide for one circular direction for the movement of the horse, lessen the distance to be traveled and reduce the work of the horse to a minimum, and that will allow the relative positions of the horse and cars to be adjusted as the conditions of the surroundings may require.

The manner in which I accomplish my object is described in the following specifications and illustrated in the accompanying drawings in which:

Figure 1 is a top plan view of the hoisting machine showing the relative positions of the cars, cables and power machine. Fig. 2 is a vertical view of the same relation of parts as in Fig. 1, the view being from the front end of the power machine towards the cars. Fig. 3 is a side elevation, the parts being in the same relative positions as in Figs. 1 and 2. Fig. 4 is an enlarged view of part of the shift mechanism located at the top of that part of the guide frame designated as the horse. Fig. 5 is an enlarged front view of that part of the mechanism shown in Fig. 4. Fig. 6 is a top plan view of part of the power machine and connected part of the shift mechanism, the main gear not being shown. Fig. 7 is a detail view of what I call a worm screw forming part of the shift mechanism. Fig. 8 is a vertical sectional view of the power machine and part of the shift mechanism on the line 8—8 Fig. 6. Figs. 9 and 10 are face views the clutch heads forming parts of the shift mechanism.

In the drawings A indicates the four vertical guides for the cars. These guides rest on a plank A¹, which forms the base of

that part of the machine located usually on the ground floor of the structure. These guides extend vertically through an aperture in the floor or floors B above. Extending over and across this aperture is a horse A². This horse consists of two base planks A³, four legs A⁴, two parallel timbers A⁵ and end braces A⁶ firmly secured together and temporarily secured to the flooring or joists B, on which the horse rests.

The guides A extend up between the parallels A⁵ and are secured thereto. Between these guides are two cars, C and C¹, which are free to be moved vertically between the base plank A¹ and the top of the horse A⁵. These cars are suspended on a cable D. Between the parallels A⁵ and rotatably supported therein are two cable wheels D¹, over which the cable D is free to run. The cable D passes from the wheels D¹ down in front of the two center guides and under two guide wheels D², secured side by side on the base plank A¹ only one of these wheels are shown in the Fig. 3. From these two wheels the cable extends to the driving wheel D³ around which it is looped several times. This wheel D³ is secured on the driving shaft of the power machine hereinafter described. Rigidly secured to each of the wheels D¹ is a ratchet wheel E, the inclination of the ratchet teeth on one wheel being opposite to that of the other. Supported in the bearings E¹ which are secured on the central part of the parallels A⁵, is a rocker shaft E² having an arm E³; secured on this rocker shaft outside the parallels is a cable wheel E⁴ and a crank E⁵. Slidably secured on the inside face of this crank is a locking bar E⁶. This bar is adapted to be locked in an immovable position on said crank by a pin E⁷ extending through said crank and through said bar, and said bar is adapted to be actuated by a lever E⁸ and a coiled spring supported on said bar, the purpose of which is hereinafter described; 100

pivotaly secured to the rocker shaft arm E³ are a pair of connecting rods F. In the free end of each of these rods is a slot F¹ adapted to allow a pin F² to slide freely therein. Each of these pins projects from the side of a pawl F³. These pawls are pivotally supported in bearings F⁴ secured on the parallels A⁵. The free end of each of these pawls is adapted to drop into and engage the ratchet teeth of each of the ratchet wheels E, and to be 110 raised and thereby released from said wheels by said connecting rods F, as shown in Fig.

5. Affixed on the frame E^1 close to the hub of the crank E^5 is a disk G , having two notches G^1 and G^2 . These notches are adapted to admit the end of the locking bar E^6 and to thereby hold said crank in a locked position for the purpose hereinafter described.

Supported on the wheel E^4 is a shift cable H . This cable runs down in front of the two center guides A under the two small guide wheels H^1 , side by side, secured to the base plank A^1 between and to the front of the cable wheels D^2 ; only one of the wheels H^1 is shown in the drawing. From these wheels the cable H passes around the wheel H^2 on the power machine and is secured thereto for the purpose hereinafter described. The cable D and cars C and C^1 are operated by a horse power machine constructed and operated as hereinafter described.

20. The base of the machine consists of a rectangular frame J , the sides and ends being halved into each other to form a flat base. On the side pieces of this base are main shaft bearings J^1 secured to the base by bolts J^2 .

25. Rotatably supported in these bearings is a shaft J^3 ; the central part of this shaft is square. Rotatably supported on this shaft close to said bearings are two gear wheels K and K^1 , the parts K^2 and K^3 forming the female parts of clutches movable on said shaft.

30. In the vertical face K^4 of each of the parts K^2 and K^3 are two recesses K^5 . Each of these recesses has a deep radial face and a base concentric with the axis of said gear. 35. This base in each recess is inclined outward from the bottom of the radial face to the face K^4 as shown in Figs. 6 and 10. Slidably supported on the square part of the shaft J^3 are the male parts of the clutch. This consists of a sleeve L having clutch heads L^1 and L^2 and a central disk L^3 . In each of these heads are two longitudinal apertures L^4 parallel with the axis of said sleeve; slidably supported in each of these apertures is a pin L^5 held in a

40. normal position by a coiled spring L^6 secured in said aperture by a plate L^7 secured to the head by screws L^8 . These pins project under the pressure of the springs from the face of the heads, and are adapted to enter the recesses K^5 in the parts K^2 and K^3 of the gears K and K^1 , and the compression of the springs by the pins permits the face K^4 to force the pins inward whenever the movement of the sleeve on said shaft forces the points of the pins 45. against said face between the recesses K^5 .

45. Pivottally supported on the frame J is a forked lever M . The forked ends M^1 of this lever are provided with anti-friction rollers M^2 , which are adapted to engage each side 50. face of the disk L^3 . The other end of the lever is provided also with a roller M^3 . Supported on the frame J is a shaft N arranged parallel with the main shaft J^3 , in the bearings N^1 , and having a lever N^2 at one end. 55. Secured on the central part of this shaft is a

worm gear N^3 . The spiral recess of this gear is adapted in depth and shape of the walls to receive the roller M^3 on the single end of the forked lever M and to limit the rotative movement to less than one full revolution of the shaft N . The walls of the end parts of this spiral are at right angles to the axis of the screw and are thereby adapted to lock the lever at the end of each movement. Supported on the frame J are two guide wheels O and O^1 secured in the box O^3 , shown in Fig. 6. The outer wheel O is adapted to guide the cable D and the wheel O^1 to guide the cable H , the cables passing beneath said wheels close to the ground so the horse may easily step over them as he circles around the machine. Secured on the top of the frame J is a spider frame bearing P . The center of this frame is elevated some distance above the sleeve L and disk L^3 . The top of this frame forms a horizontal bearing P^1 . Rising vertically from the bearing P^1 is a stud P^2 , the end of which is threaded and provided with a nut P^3 . Rotatably supported on the bearing P^1 and stud P^2 of the spider P is a main gear wheel R , the teeth of which mesh into the gears K and K^1 as shown in Fig. 8. The mesh of these gears is maintained by rollers R^1 revolvably secured on the studs R^2 supported in the bearings P^1 . These rollers are adapted to engage the smooth surface of the gear R and to thereby prevent it from rising from the gears beneath it. Forming a part of the hub R^3 of this gear is a stirrup R^4 adapted to allow the end of the sweep S to project through. On one of the spokes of the gear R is a vertical bracket R^5 adapted to support the sweep in a horizontal position. The sweep S is provided with an eye bolt S^1 , to which the harness of the horse is attached and an eye bolt to which a chain or rod S^2 can be attached to form a brace from one of the spokes of the gear for the purpose of strengthening the sweep.

50. When my invention is constructed as described and the several parts erected and connected its operation is as follows: The cable H is adjusted so that when the car C is down and the car C^1 is up the crank E^5 is locked in the notch G^2 as shown in Fig. 2, and the lever N^2 is in a horizontal position, the lever M is in the end of the worm gear and locked in that position by the walls of those parts of the gear being at right angles with the axis. The sleeve is thereby held with the face of the clutch head L^2 close to the clutch face of the gear K^1 , the sliding pins under pressure of the springs being forced to the full depth of the recesses K^5 and in contact with the radial faces therein, the pins at the other end of the sleeve just clearing the clutch face of the gear K . In this position the cars are in position for the placing or removal of the loads to be carried. The operator on the floor at the top of the hoisting ma-

chine, grasps the lever E^8 and crank E^5 , thereby releasing the bar E^6 from the notch G^2 in the disk G , moves the crank to the left till the bar E^6 enters the notch G^1 . The 5 rocker shaft is thereby rotated; the arm E^3 moves the connecting rods F over to the right raising the pawl out of contact with the ratchet wheel E on the right and allows the pawl on the left to drop on the ratchet wheel 10 on the left and to thereby prevent any reverse movement of the ratchet and cable wheel. This movement of the crank transmitted by the cable H to the shaft N rotates the worm gear N^3 , moves the lever M , which 15 thereby forces the sleeve to the left and its clutch head L^1 into engagement with the gear K , thereby locking those parts and releasing the gear K^1 which is then free to rotate on the shaft J^3 . The horse attached to the sweep S 20 circles to the left and thereby rotates the gear R , gear K , shaft J^3 and cable driving wheel D^3 , and cable D , thereby raising the car C and lowering the car C^1 . The horse is stopped when the car C^1 reaches the bottom 25 and the pawl and ratchet wheel holds the load till it is removed. The crank when moved to the right reverses the movements of the machine just described. When it is most convenient to operate the cars from the 30 ground, the bar E^6 is drawn by the lever E^8 from contact with the disk G and locked by the insertion of the pin E^7 in the crank and bar, then the operator by moving the lever N^2 controls the movements of the machine, 35 the movements of the shaft N being transmitted to the rocker shaft and ratchets by the cable H .

What I claim as new and desire to secure by Letters Patent is:

- 40 1. In a hoisting machine of the kind described, the combination consisting of a main shaft having a cable wheel, said shaft being rotatably supported in suitable bearings and frame, the central part of said shaft 45 being angular in cross section; a double headed sleeve slidably supported on the angular part of said shaft and rotatable with it, said sleeve having a central disk. Each head of said sleeve having longitudinal apertures parallel with the axis of said sleeve and in each of said apertures, a spring pressed clutch pin extending normally from the vertical face of each of said heads and slidably 50 therein; a pair of clutch gears rotatably supported on said shaft between each bearing and each head of said sleeve, the vertical face of each of said gears having a pair of recesses concentric with the axis of said gears and inclined from the face of the gear to a depth 55 therein adapted to receive and hold the clutch pins when projecting from the heads of said sleeve; a horizontal gear supported above and meshed in both of said clutch gears having a stirrup and bracket adapted 60 to support a sweep therein; a worm gear 65
- shaft located in the same plane and parallel with said main shaft; a worm gear secured on the central part of said shaft and rotatable with it; a double ended lever pivotally supported in the same plane and between said main and worm gear shafts, a single end of said lever being engaged between the walls of said worm gear and the forked end of said lever engaging both sides of the disk of said sleeve, the partial rotation of said worm gear 70 operating said lever and thereby pressing its forked end against said disk and moving said sleeve on its shaft and one of its heads into contact with one of said clutch gears; means on the ends of the worm gear shaft for partially rotating said shaft in either direction and thereby reversing the movement of said sleeve and the rotation of said main shaft and cable wheel during the rotation of said horizontal gear by said sweep. 75
2. In a horse power hoisting machine, the combination with the frame; of a main shaft and wheel affixed thereon, supported in said frame; a double headed sleeve having a central disk, said sleeve being slidably secured 80 on said shaft and adapted when rotated to turn said shaft with it; a pair of clutch gears journaled on said shaft adapted to be engaged by the heads of said sleeve; a main gear meshed with said clutch gears and 85 adapted to rotate them; means for rotating said main gear; a worm gear shaft and means for partially rotating it in either direction; a worm gear affixed on said shaft; a lever engaged with said worm gear and said disk on 90 said sleeve adapted when moved by rotary movement of said worm gear to move said sleeve in either direction on its shaft into contact with one or other of said clutch gears. 95
3. In a horse power hoisting machine, the combination with the frame and main shaft supported therein, said shaft having a cable wheel; of a sleeve slidably secured on said shaft, each end of said sleeve containing a pair of pins parallel with said shaft, each of said pins being slidable in said sleeve and adapted to project therefrom under pressure of a spring inclosed in said sleeve and in contact with the pin, said sleeve having a central disk by which it is moved longitudinally 105 on said shaft; and a pair of worm gears journaled on said shaft adapted to be engaged alternately by the pins in said sleeve; a main gear wheel enmeshed with and adapted to rotate said gears on said shaft, a sweep attached 110 to said gear by which it is rotated; a shift shaft and worm thereon, said shaft being parallel with said main shaft, and a pivoted lever in engagement with said worm gear and with the disk on said sleeve whereby said sleeve is moved longitudinally on said main shaft and into engagement with said gears, when, said lever is actuated by the partial rotation of said shift shaft, and means for 115 operating said shaft. 120
4. In a horse power hoisting machine, the combination with the frame and main shaft supported therein, said shaft having a cable wheel; of a sleeve slidably secured on said shaft, each end of said sleeve containing a pair of pins parallel with said shaft, each of said pins being slidable in said sleeve and adapted to project therefrom under pressure of a spring inclosed in said sleeve and in contact with the pin, said sleeve having a central disk by which it is moved longitudinally 125 on said shaft; and a pair of worm gears journaled on said shaft adapted to be engaged alternately by the pins in said sleeve; a main gear wheel enmeshed with and adapted to rotate said gears on said shaft, a sweep attached to said gear by which it is rotated; a shift shaft and worm thereon, said shaft being parallel with said main shaft, and a pivoted lever in engagement with said worm gear and with the disk on said sleeve whereby said sleeve is moved longitudinally on said main shaft and into engagement with said gears, when, said lever is actuated by the partial rotation of said shift shaft, and means for 130 operating said shaft.

4. In a horse power hoisting machine, the combination with the frame, the main shaft and cable wheel supported therein, a sleeve slidably secured on said shaft, said sleeve having a pair of spring pressed pins in the ends thereof; of a pair of gears journaled on said shaft, each of said gears having a plurality of recesses in the vertical face, said recesses being concentric with the axis of the gears, and inclined from the face inward to a depth sufficient to receive said pins in said sleeve, the inclination of said recesses being adapted to regulate the sliding movement of said pins into said recesses; and a main gear wheel enmeshed with said gear, and a sweep attached thereto whereby said gears are rotated; a shift shaft and worm gear thereon, and a pivoted lever engaged by said worm gear and in engagement with the disk on said sleeve, whereby said sleeve is moved longitudinally on said main shaft into engagement with said gears, when said shift shaft is partly rotated, and means for operating said shaft.
5. In a horse power hoisting machine of the kind described, the combination with the frame, the main shaft therein, the sleeve, and gears thereon; of a main gear wheel rotatably supported on a vertical shaft, said wheel being provided with a stirrup and bracket adapted for the support and adjustment therein of a sweep for operating said wheel, said wheel being enmeshed with and adapted to rotate said gears on said main shaft; and a shift shaft and worm gear thereon, and a pivotal lever engaged by said worm gear and in engagement with said sleeve, whereby said sleeve is moved longitudinally on said shaft by the partial rotation of said shift shaft, and means for operating said shaft.
6. In a horse power hoisting machine of the kind described, the combination with the frame, main shaft therein, sleeve slidable on said shaft having spring pressed slidable pins therein, clutch gears journaled on said shaft having inclined concentric recesses adapted to admit said pins, main gear wheel enmeshed with said gears, having a stirrup and bracket; of a shaft supported in said frame parallel with said main shaft and a worm gear thereon, said gear being adapted to admit the end of a lever between its walls, the angle or inclination of said walls being adapted to move the end of said lever horizontally and to lock said lever at each end of said worm till said shaft and worm is reversed, and a lever pivotally supported on said frame, said lever having a single end engaged in said worm, and a forked end in engagement with a disk part of said sleeve, whereby said sleeve is moved longitudinally on said main shaft, and means for operating said shift shaft.
7. In a horse power hoisting machine of the kind described, the combination with the frame, a main shaft therein, a sleeve slidable on said shaft having spring pressed slidable pins in the ends thereof, a pair of gears journaled on said shaft having inclined concentric recesses adapted to admit said pins, a gear wheel having a stirrup and bracket for the support of a sweep, said gear wheel being enmeshed with said gears on said shaft; a shift shaft in said frame and worm gear thereon; of a centrally pivoted double ended lever supported on said frame, one end of said lever adapted to be engaged and moved by said worm gear, the other end being adapted to engage said sleeve and to move it longitudinally in either direction on said shaft when actuated by said worm on said shift shaft, and means for operating said shaft, as described.
